UNITED STATES PATENT OFFICE.

GUSTAV JOHANNES PAUL KOTHE, OF REVAL, RUSSIA, ASSIGNOR OF ONE-HALF TO
MARTIN GUMPEL, OF MOSCOW, RUSSIA.

COMBUSTION-TURBINE.

1,112,809.

Specification of Letters Patent.

Patented Oct. 6, 1914.

Application filed March 18, 1912. Serial No. 684,386.

To all whom it may concern:

Be it known that I, GUSTAV JOHANNES PAUL KOTHE, a subject of the King of Prussia, Germany, residing at Reval, Russia, **5** have invented a new and useful Combustion-Turbine, of which the following is a specification.

This invention relates to a combustion turbine of novel construction, and more particularly to improved means for causing a **10** combustion of the mixture within rotating temporarily closed chambers, that are subsequently brought into communication with the turbine pockets.

15 The invention also comprises means for cleansing the combustion chambers in a novel and effective manner and other novel features which are more fully pointed out in the appended specification and claims.

20 In the accompanying drawing: Figure 1 is a plan view of a combustion turbine embodying my invention; Fig. 2 a vertical longitudinal section on line 2—2, Fig. 1; Fig. 3 a cross section on line 3—3, Fig. 2; Fig. 4

25 a left hand end view of Fig. 1, with the governor and cover removed; Fig. 5 a cross section on line 5—5, Fig. 2; Fig. 6 a cross section on line 6—6, Fig. 2; Fig. 7 an enlarged longitudinal section through the regulating

30 valve which simultaneously serves for admitting the combustible fuel to the fuel supply chamber; Fig. 8 an end view of one of the combustion chamber-stems, and Fig. 9 a detail section through part of the turbine

35 wheel and gas inlet channel.

My improved combustion turbine comprises essentially a turbine wheel *i*, the shaft *t* of which is rotatably mounted in a corresponding bearing *w*₁ of the turbine casing

40 *w*. To wheel *i* is firmly connected a spindle *p* carrying a pinion *q* which through gear wheels *r*, *r*₁ transmits motion to the internally toothed rim *s* of a head *o*₁. The latter forms part of a hollow shaft *o* that encloses

45 spindle *p* and carries a pair of relatively fixed distributing disks *m*, *n* constituting a valve motion. Between disks *m* and *n* is arranged a number of combustion chambers *e* that rotate with said disks, the

50 drawing being based upon the employment of three of such chambers. To the outer end of shaft *t*, is secured the rotary member of a conventional air compressor *a*, which compressor is through pipe *b* connected with an

55 air chamber *c* arranged within the station-

ary frame section *w*₂. The latter is firmly mounted upon a hollow base plate *D*₁ containing preferably a liquid fuel chamber *D*. The combustible liquid is raised from chamber *D* by means of a pump *x*, the plunger *x*¹ **60** of which is driven by an eccentric *x*₂ (Fig. 3). From pump *x*, the liquid is conveyed by pipe *z* and the hollow casing *B*₁ of one of the regulating valves *B* into a supply chamber *y*, in which said liquid is temporarily stored under a certain pressure. In order to prevent the generation of an excessive pressure within chamber *y*, a spring-controlling safety valve *E* is provided which causes the surplus liquid to be automatically **65** returned into chamber *D*. The number of valves *B* corresponds to the number of combustion chambers *e*, each valve *B* controlling an exit port *g* of casing *w*₂. Valves *B* are operated from a suitable governor *A* **70** through a link and lever system *A*₁, so that such quantities of liquid fuel are discharged into ports *g* as correspond to the temporary speed and power of the turbine. Corresponding to the three combustion chambers **75** *e* employed, air chamber *c* communicates with three sets of segmental passages *d* and three sets of similar smaller passages *h* that are adapted to consecutively register with the segmental inlet ducts *e*₁ formed within the **80** corresponding stems *e*₂ of chamber *e*, while central inlet ducts *f* of said stems are adapted to register with ports *g* of chamber *c*.

85 Chambers *e* are adapted to consecutively communicate through outlet passages *H* with channels *h*, *h*₁ and *h*₂ which are formed within the stationary turbine section *w*₃. Of these, channels *h* convey the ignited mixture toward high pressure turbine pockets *i*₁, while the channels *h*₁ convey the remainder of said mixture from chambers *e* toward low pressure pockets *i*₂. If desired, the latter may be employed as medium pressure pockets, and additional low pressure pockets *i*₃ may be used as illustrated in Fig. 2, **90** the channels leading to said last named pockets having however been omitted for the sake of greater clearness. The channels *h*₂ establish communication between the combustion chambers *e* and an exhaust *l* that **95** leads into the atmosphere.

100 In order to protect disks *m* and *n* against excessive heating, they are cooled by passing water through chambers *u*. For a similar purpose turbine wheel *i* is provided with **105** 110

peripheral ribs i_4 that draw a cooling current of air through openings w_4 of casing w , so that said wheel is properly cooled, while the passages conducting the pressure medium toward said wheel, are unaffected.

As the operation is the same with each of the three combustion chambers and coöperating parts, it will be described with reference to only one of said chambers. During the operation of the turbine, compressor a will maintain chamber c charged with compressed air, while pump x will cause chamber y to be permanently filled with the combustible liquid under pressure. In order to describe the cycle of operations in the proper order, it may be assumed that during the rotation of distributing disks m and n in the direction of the arrow (Fig. 6), passages e_1 become temporarily alined with ducts d , so that air under pressure will be admitted into chamber e . Immediately after being thus charged, duct f registers with port g , so that such an amount of the combustible liquid is sprayed into chamber e as is determined by the position of governor A . The mixture thus produced within chamber e will be ignited by the inherent heat of the chamber, produced by the rapidly following ignitions, which heat considerably exceeds the igniting temperature of the combustible. Owing to the fact that while duct f is closed immediately after the admission of the liquid fuel into chamber e , duct H is also closed by a solid portion of stationary turbine section w_3 , the combustion takes place at a constant volume within a closed chamber. As soon as the combustion has been completed, duct H becomes alined with channel h so as to convey the high pressure gases toward pockets i_1 of wheel i and thus rotate the latter. During the continued rotation of disk n , duct H will register with channel h_1 so as to admit the remainder of the gases into low pressure pockets i_2 to assist in the rotation of wheel i . After this operation, ducts e_1 become alined with passages k while at the same time duct H registers with channel h_2 , so that the residual combustion gases will be expelled from chamber e through duct H , channel h_2 and exhaust l by means of the air current admitted through passages k . Ducts e_1 will now register with the next set of passages d , whereupon the operation described is repeated. In starting the turbine, wheel i is slowly rotated by any convenient means not shown, while chambers e are exteriorly heated in suitable manner, for instance by soldering lamps, until ignition takes place.

Although the drawing shows three sets of gas and liquid inlets, it is obvious that this number as well as the number of pressure steps for the turbine pockets may be changed to answer different conditions without departing from the spirit of my invention.

It will be seen that by the construction described, the pressure generated by the combustible mixture has no objectionable influence upon the valve motion, while owing to the peculiar arrangement of the heated rotating combustion chambers between the stationary parts of the machine, a tight closure of the combustion chamber is obtained, without consuming an objectionably high energy. So also by expelling the mixture residues from the combustion chambers directly into the exhaust, the quantity and pressure of the cleansing air is correspondingly reduced.

I claim:

1. In a combustion turbine, a plurality of rotating combustion chambers adapted to retain the heat produced by combustion, and a valve-motion controlling said chambers, said valve-motion being so constituted as to be relieved of the pressure of the combustible charge prior and subsequent to combustion. 80
2. In a combustion turbine, means for supplying compressed air, means for supplying a combustible, a turbine wheel, a combustion chamber adapted to retain the heat produced by combustion, and a valve-motion adapted to consecutively connect the combustion chamber with the compressed air supplying means, with the combustible supplying means, and with the turbine wheel. 90
3. In a combustion turbine, means for supplying compressed air, means for supplying a combustible, a turbine wheel, an exhaust, a combustion chamber having an inlet end and an outlet end and adapted to retain the heat produced by combustion, a valve motion adapted for consecutively connecting the inlet end of the combustion chamber with the compressed air supplying means and with the combustible supplying means, while the outlet end is closed, for connecting said outlet end with the turbine wheel 100 while the inlet end of the combustion chamber is closed, and for finally connecting the inlet end of said chamber with the compressed air supplying means while the outlet end is connected with the exhaust. 110
4. In a combustion turbine, means for supplying compressed air, means for supplying a combustible, a turbine wheel, means for cooling the same, a combustion chamber adapted to retain the heat produced by combustion, and a valve-motion adapted to consecutively connect the combustion chamber with the compressed air supplying means, with the combustible supplying means, and with the turbine wheel. 120
5. In a combustion turbine, means for supplying compressed air, means for supplying a combustible, a turbine wheel, peripheral cooling ribs provided on said wheel, a combustion chamber adapted to retain the 130

heat produced by combustion, and a valve-motion adapted to consecutively connect the combustion chamber with the compressed air supplying means, with the combustible supplying means, and with the turbine wheel.

6. In a combustion turbine, means for supplying compressed air, means for supplying a combustible, a turbine wheel, an exhaust, a combustion chamber having an inlet end and an outlet end and adapted to retain the heat produced by combustion, a valve motion adapted for consecutively connecting the inlet end of the combustion chamber with the compressed air supplying

means and with the combustible supplying means, while the outlet end is closed, for repeatedly connecting said outlet end with the turbine wheel while the inlet end of the combustion chamber is closed thereby supplying a pressure medium of stepwise decreasing pressure to said wheel, and for finally connecting the inlet end of said chamber with the compressed air supplying means while the outlet end is connected with the exhaust.

GUSTAV JOHANNES PAUL KOTHE.
